United States Patent

Des. 242,469
Patented Nov. 23, 1976

242,469

TELLER STATION

Dagmar L. Arnold, Woodstock, N.Y., and Dallas G. Molerin, and Philip C. Yenerich, San Jose, Calif., assignors to International Business Machines Corporation, Armonk, N.Y.

Filed June 9, 1975, Ser. No. 584,786

Term of patent 14 years

Int. Cl. D14—02

U.S. Cl. D26—5 C

FIG. 1

FIG. 2

FIG. 1 is a front perspective view of a teller station, showing our new design; and

FIG. 2 is a rear perspective view thereof.

The bottom of the device is substantially plain and unornamented.

We claim:

The ornamental design for a teller station, substantially as shown and described.
